UNITED STATES PATENT OFFICE

LEO T. BLAGG, OF KANSAS CITY, MISSOURI, ASSIGNOR OF ONE-HALF TO ERNEST G. SNYDER, OF KANSAS CITY, MISSOURI

DESIGN FOR A COMBINATION SMOKER'S SET

Application filed April 11, 1930. Serial No. 35,218. Term of patent 3½ years.

To all whom it may concern:

Be it known that I, LEO T. BLAGG, a citizen of the United States, residing at Kansas City, in the county of Jackson and State of Missouri, have invented a new, original, and ornamental Design for a Combination Smoker's Set, of which the following is a specification, reference being had to the accompanying drawing, forming a part thereof, in which a perspective view of my new design is shown.

I claim:

The ornamental design for a combination smoker's set, as shown.

LEO T. BLAGG.
